(57) **CLAIM**

The ornamental design for a golf glove, as shown and described.

DESCRIPTION

FIG. 1 is a back perspective view of a golf glove;
 FIG. 2 is a back plan view thereof;
 FIG. 3 is a left-side elevation view thereof;
 FIG. 4 is a front plan view thereof;
 FIG. 5 is a right-side elevation view thereof;
 FIG. 6 is an elevation view of the top (finger tip) end; and,
 FIG. 7 is an elevation view of the bottom (wrist opening) end thereof.

The broken lines shown on the golf glove is stitching. The stippling in the drawings represents contrast in fabric. The crosshatched pattern, although shown intermittently, is meant to represent fabric, and is understood to be distributed uniformly over the surfaces of the claimed design upon which it occurs.
